United States Patent Office

Des. 183,026

Patented June 10, 1958

183,026

CHECK OUT STAND

Leslie V. Slikkers, Grand Rapids, Mich., assignor to The Bulman Corporation, Grand Rapids, Mich., a corporation of Michigan

Application February 3, 1956, Serial No. 40,030

Term of patent 14 years

(Cl. D80—2)

Fig. 1.

Fig. 2.

Fig. 3.

Fig. 4.

Fig. 1 is a plan view of a check out stand showing my new design,

Fig. 2 is a side elevation of the same,

Fig. 3 is a perspective view of the same showing one side and one end, and

Fig. 4 is a perspective view of the same showing the opposite side and end than those shown in Fig. 3.

I claim:

The ornamental design for a check out stand, as shown.
